PORTABLE CONTAINER

Daniel E. Spaulding, Syracuse, N. Y., assignor to
 Continental Can Company, Inc., New York,
 N. Y., a corporation of New York

Application August 13, 1942, Serial No. 454,697

2 Claims. (Cl. 220—92)

This invention relates to portable containers and more particularly to closed top containers equipped with carrying bails.

Conventionally constructed containers of the class referred to are equipped with a generally semicircular bail extending across the container and having its opposite ends projected downwardly for connection to mounting ears secured to the container side wall or walls at a level somewhat below the top of the container. When the bail is not used for carrying, for example during storing or shipping of the container, the bail is folded down against the side of the container. This not only interferes somewhat with the compact storing of containers but is apt to result in bending or otherwise damaging the bails, or in scratching or marring labels or markings on the container.

It heretofore has been proposed to eliminate or minimize these difficulties by constructing and mounting the bail in such manner that when not in use it will be turned or folded down against the top of the container. Still more particularly the present invention relates to this class of bail-equipped container construction and the general aim or purpose of the invention is to provide an improved, simple, and strong construction in which a bail is so mounted on or connected to a container that when in use for carrying the container, the bail will be disposed in the same or substantially the same position as a conventional bail, and when not in use may be positioned snugly with respect to the top of the container without extending across or around the container side wall.

An object of the invention is to provide a portable closed top container with a carrying bail so mounted on the container as to be capable of being folded down against the container top wall and below the top edge of the container side wall.

Another object of the invention is to provide bail type carrying means in combination with or especially suited for attachment to a container of the kind having a top and side wall seam connection which extends outwardly from the side wall to provide a flange, and to so construct the carrying means as to be easily attachable to the flange. A further object is to provide an externally flanged portable container and bail type carrying means therefor in which a bail is hinged to a pair of oppositely disposed bail anchors secured to the container in a manner to engage exterior surfaces only of the container and pref-

erably to engage the bottom, outside, top, and inside faces of the container flange.

Other objects will become apparent from a reading of the following detailed description, the appended claims, and the accompanying drawing.

In the drawing:

Figure 1 is a perspective view of a container and bail type carrying means embodying the invention, a part of the container side wall and bottom being broken away.

Figure 2 is a fragmentary top plan view drawn on an enlarged scale and showing anchoring means for attaching a carrying bail to a container.

Figure 3 is a fragmentary vertical section drawn on an enlarged scale, a bail anchor and a portion of the bail being shown in elevation.

Figure 4 is a view similar to Figure 3 but showing a modification.

Figure 5 is a fragmentary top plan view of the modification shown in Figure 4.

Figure 6 is a fragmentary top plan view of a container equipped with a bail anchor embodying a further modification.

Figure 7 is a fragmentary vertical section through a container and showing in elevation the bail anchor shown in Figure 6.

Figure 8 is a fragmentary vertical section at right angles to Figure 7.

In the embodiment of the invention illustrated in Figures 1 to 3 inclusive, a bail generally designated A is hinged to bail anchor members B which are connected or secured in any suitable manner to a container C.

The container includes a side wall 1, and top and bottom walls 2 and 3 secured to the side wall by double seams of well known form shown respectively at 4 and 5. The top wall 2 is disposed below the top of the side wall 1, thereby providing a recess or depression 6 surrounded by the seam 4 or, otherwise stated, by the upper portion of the side wall 1.

In accordance with the invention, the bail A is hinge-connected to the container within the depression 6 and is so shaped and sized that when not in use for carrying the container, the bail may be folded down against the top wall 2 and to be then nested within the depression 6 so as not to protrude above the container. For so mounting the bail, the anchors B are connected to the container at opposite sides of the latter. Each anchor may be formed of strip or wire-like material and includes two attaching portions 7 and 8 and a portion generally designated 9 con-

necting the portions 7 and 8 and being formed with an eye 10 through which the associated end of the bail A is looped as by an eye 11. Each attaching portion has component portions extending respectively in contact with the bottom, outside, top, and inside faces of the outside flange provided by the seam 4, thus snugly embracing and reinforcing the seam. Within the depression 6 the attaching portions 7 and 8 are provided with horizontally extending portions 12 and 13 which converge inwardly and merge in the eye 10.

When the container is to be stored or shipped, the bail A may be folded down to the position shown in full lines in Figure 1 wherein it is disposed within the depression 6 so as not to interfere with stacking or boxing of a plurality of containers. When a container is to be carried individually, the bail is turned up to the position shown in dotted lines in Figure 1 wherein it is disposed relatively to the container in the same general manner as a conventional carrying bail.

The anchors B are stout enough to reinforce the connection between the side and top walls 1 and 2, thereby reducing the danger of damaging the seam 4 sufficiently to cause a leak.

The modified embodiment shown in Figures 4 and 5 includes a bail anchors B' each formed to include two attaching portions 7a and 8a and a connecting portion generally designated 9a formed with an eye 10a through which the associated bail eye 11 is looped. The attaching portions 7a and 8a are the same as the attaching portions 7 and 8 described with reference to Figures 1 to 3 but the connecting portions 9a are formed differently. Each of the modified connecting portions includes a horizontal portion 14 extending from the attaching portion 8a within the depression 6 and in contact with the inside face of the seam 4. The attaching portion 7a has extending therefrom a horizontal portion 15 projecting away from the inside face of the seam. The horizontal portions 14 and 15 merge in the eye 10a which lies substantially in a vertical plane radial with respect to the container C.

In the modification shown in Figures 6 and 7, the bail anchor B² is provided with a single attaching portion 7b which is formed similarly to the attaching portions 7, 8, 7a, and 8a previously described, engaging the seam flange in the same manner. A horizontal portion 16 extends from the attaching portion 7b in contact with the flange inside face and is turned inwardly to form a horizontal portion 17 projecting away from the flange 4 and terminating in an open eye or hook 10b adapted to receive an eye on the bail.

It will be observed that in both illustrative embodiments of the invention, the anchors are shaped to embrace the bottom, outside, top, and inside faces of the double seam 4, thereby securely attaching the anchors to the container and reenforcing the joint between the side and top walls 1 and 2.

The constructions shown herein embody the invention in the forms now preferred, but it will be understood that changes may be made without departing from the invention as defined in the claims.

I claim:

1. The combination with a container having a side wall, a top wall, and an outside seam connection between said walls, said connection projecting outwardly beyond said side wall, and said top wall being disposed below the top of said seam to provide a depression surrounded by said seam; of a bail type carrying means comprising two bail anchors secured to said container at opposite sides thereof respectively, and a bail hinged at its opposite ends to said anchors, each of said anchors comprising two attaching portions respectively engaging the bottom, outside, top, and inside faces of said seam at points spaced circumferentially of said seam, one of said attaching portions having extended therefrom a horizontal portion disposed within said depression and in contact with the inside face of said seam, and the other of said attaching portions having extending therefrom a horizontal portion projecting away from said inside face of the seam, said two horizontal portions merging in an eye substantially in a plane radial with respect to the container, opposite ends of said bail respectively being looped through the anchor eyes.

2. The combination with a container having a side wall, a top wall, and an outside rolled seam connection between said walls, said connection projecting outwardly beyond said side wall, and said top wall being disposed below the top of said seam to provide a depression surrounded by said seam; of a bail type carrying means comprising two bail anchors secured to said container at opposite sides thereof respectively and contacting only exterior surfaces of said container, and a bail hinged at its opposite ends to said anchors, each of said anchors comprising two attaching portions respectively engaging the bottom, outside, top, and inside faces of said seam at points spaced circumferentially of said seam, said attaching portions respectively having projecting therefrom horizontal portions which converge towards each other and merge in an eye, opposite ends of said bail respectively being looped through the anchor eyes.

DANIEL E. SPAULDING.
